UNITED STATES PATENT OFFICE

WILLIAM F. DIETRICHSON, OF ST. LOUIS, MISSOURI, ASSIGNOR TO AMERICAN CAR AND FOUNDRY COMPANY, OF NEW YORK, N. Y., A CORPORATION OF NEW JERSEY

DOOR CLOSING DEVICE FOR CARS

Application filed February 27, 1930. Serial No. 431,868.

This invention relates to devices for closing the drop doors which form the bottoms of cars used for transporting material in bulk, generally coal, sand or a similar article and which doors are operated to dump the car ladings into bins or chutes while the cars continue in motion and it is an object of this invention to provide a device which will automatically close the doors of such cars while they continue in motion and which will close the doors of such cars without injury to the doors or to the device despite variations in the speeds of the cars and in the height of the doors, when closed, above the rails. It is also an object of this invention to provide a device of the class described which will automatically return towards a predetermined position after each operation for engagement with the next succeeding door, which will be positively stopped in the predetermined position with a minimum blow to the device and which will yield to prevent damage to doors which are slightly lower than the standard height above the rails.

25 In the drawings:

Fig. 1 is a view in side elevation of a door closing device constructed in accordance with this invention in position to engage with the leading door of a car to close the same, it being understood that the car is moving towards the right in this figure;

Fig. 2 is a partial view, similar to Fig. 1 in which the car has moved further to the right than in Fig. 1 and the leading door has been raised to closed position by the door closing device and is about to pass therefrom;

Fig. 3 is a partial view similar to Figs. 1 and 2 in which the car has moved still further to the right; the leading door has passed from the door closing device and the door closing device has moved back towards its normal position and has engaged with the following door;

Fig. 4 is a top plan view of the door closing device drawn to a larger scale and shown detached from the track;

Fig. 5 is a view in front elevation of the door closing device, parts being broken away to show other parts more clearly and the de-

vice being shown in solid lines in the raised or final position and in broken lines in its normal or lowered position in which it initially contacts with the doors; and

Fig. 6 is a view in end elevation, looking from the right in Fig. 5 and showing the door closing device in its raised position.

In the drawings a door closing means 1 constructed in accordance with this invention is shown in connection with a car 2 of suitable construction for use therewith, the car being of the drop bottom type having a plurality of drop doors which are adapted to be operated for dumping by suitable door tripping mechanism and afterwards to be engaged successively by the door closing means shown clearly in side elevation in Fig. 5 whereby said doors are forced to closed position. The door closing device 1 comprises a frame formed of spaced elements 4 and 6, I-beams in the instance shown, and an upper frame member indicated generally at 7 constituting a tie between the elements 4 and 6 as will be more clearly described hereinafter. The elements 4 and 6 have bearing brackets 8 attached to their lower ends and are journaled on pins 10 mounted in bearing brackets 12 attached to a support or base member 14 shown as a channel having its web 16 arranged horizontally and its flanges projecting downwardly. The base member 14 is attached to a suitable foundation 18 by means of suitable fasteners such as the bolts 20; the foundation 18 and the door closing device being positioned between track rails in order that the door closing member may cooperate with the open doors of the drop bottom cars during movement of said cars whereby to force the doors to closed position. At their upper ends the I-beams 4 and 6 have bearing brackets 22 attached thereto and the tie or upper frame member 7 extends between the elements 4 and 6 and comprises a pair of angles 28 having inwardly projecting flanges to which are attached bearing brackets 30 through which pins 24 and 26 extend, said pins being mounted in brackets 22 at the upper ends of the elements 4 and 6. The member 7 thus connects the elements 4 and 6 as will be ap-

parent. The I-beams 4 and 6 serve as links to connect the tie member formed of the angles 28 to the base 14 and form with the tie member a frame all the joints of which are pivot joints and which always keeps the tie member substantially parallel to the base member 14.

The pin 26 in the upper end of the I-beam 6 projects beyond the bearing brackets 22 and has mounted thereon bearing brackets 32 attached to an inverted pan-shaped door engaging member 34 substantially adjacent one end thereof. The other end of the door engaging member 34 is supported upon a plurality of springs 36 which bear upon a plate 38 which ties the inwardly projecting flanges of angles 28. The springs 36 are secured in position by studs 40 attached to the member 34 and upward movement of the end of the member 34 is limited by a bolt 42 which extends through the plate 38 and is attached to the door engaging member 34 as at 44.

To the I-beam 4 is attached a plurality of cables 46 which extend over pulleys 48 and are attached to a weight 50. The pulleys 48 are supported by a frame comprising spaced vertical angles 54 and spaced inclined angles 55, the vertical angles 54 being attached at their lower ends to the web 16 of the base 14 by angle gussets 56 and connected at their top by a tie plate 58. The inclined angles 55 are attached to the web 16 of the base member 14 by angle gussets 60 and are connected together adjacent their upper ends by a tie plate 62. The upper ends of the adjacent vertical angle 54 and inclined angle 55 are connected by side tie plates 64 provided with openings for receiving the end of a pin 52 upon which the pulleys 48 are mounted. The weight 50 has its sides notched as at 66 to receive the inwardly projecting flanges of the angles 54 which serve as guides for the weight 50 and its lower end is notched to fit the inwardly projecting portion of the gussets 56.

To limit the movement of the I-beams or links 4 and 6 there is provided a plurality of substantially pan-shaped stop members 70 which are joined back to back and secured by their flanges 72 to the web 16 of the base member 14. The members 70 are provided with flanges 74 which are engaged by the web of the I-beam 6 when the device has been moved to its fully raised position by engagement with a door and with flanges 76 which are engaged by the web of the I-beam 4 when the device is in its normal or lowered position.

In the operation of this device, as a car moves to the right in Figs. 1, 2 and 3, the leading door 78 will engage with the rounded end 80 of the door engaging member 34 and shift the door closing device from its normal position, as shown in Figs. 1 and 5, until the web of I-beam 6 engages with the flanges 74

of the stop members 70, the door engaging member 34 being raised as the device is shifted from one position to the other. When the I-beam 6 engages the stop members 70, the door 78 rides upon the upper surface of the door engaging member 34 and passes thereover holding the device in the raised position. As the car passes along the member 34 raises the door to a position in which the latches 82 will engage with the lugs 84 on the door and hold the door in closed position. After the door 78 has passed beyond the door engaging member 34 the door closing device will return to its normal position. It will be noted that when the door engaging member 34 has been moved to its fully raised position with the web of the I-beam 6 in engagement with the flanges 74 the weight 50 rests upon the base 14 and there is slack in the cables 46. This slack is left in order to permit of the ready movement of the device from its fully raised position towards its normal position, the slack being taken up before the device has returned to its normal position whereupon the weight 50 tends to slow the movement of the device and lessen the shock of the I-beam 4 against the flanges 76 of the stop members 70.

In order to lessen the blow of the door against the curved end 80 of the door engaging member 34 there is provided a member 86, shown as a channel member, which extends across the chute or hopper opening and is positioned to engage the lower portion of the door and initiate the closing movement of the door before the door engages with the door engaging member 34. In order to insure the full closing movement of the doors despite slight variations in the height of the doors above the rails, the springs 36 are provided which elevate the trailing end of the door closing member 34 to a position above that necessary to close the doors normally. The springs 36, however, yield to permit the doors to pass over the member 34 and insure an elevation of the door closing member 34 which will close doors which are slightly higher when closed than the normal door.

After closing the leading door 78 and being released thereby the door closing device returns towards its normal position to be operated and released by the following doors 88 and 90 in the same manner. While the preferred form of the invention has been shown and described it is to be understood that the invention is not limited to the exact details of construction shown and described as it is apparent that various modifications thereof within the scope of the claims will occur to persons skilled in the art. It is also to be understood that the word frame used in this specification is not to be restricted to a construction which includes merely spaced members such as 4 and 6 as obviously the construction of the supporting means for the

door engaging element 34 may assume other and desired constructions.

What is claimed is:

1. In a door closing device, a support, a frame mounted thereon and capable of limited shifting in two directions, and a door engaging member supported by and pivotally connected at one end to said frame. 5
2. In a door closing device, a support, a frame mounted thereon, a door engaging member mounted on said frame and pivotally connected thereto at one end, and yielding means for supporting the other end of said member on said frame. 10
3. In a door closing device, a support, a frame pivotally mounted thereon, a door engaging member supported by the frame and pivotally connected at one end thereto and means limiting the movement of said frame. 15
4. In a door closing device, a support, a frame pivotally mounted thereon, a door engaging member carried by the frame and pivotally connected at one end thereto, and means slowing the movement of said frame 20 in one direction.
5. In a door closing device, a door engaging member, a pivotally jointed and supported frame pivotally supporting an end of said member and resilient means on said frame yieldingly supporting the other end of said member. 25
6. In a door closing device, a door engaging member, a pivotally jointed frame pivotally supporting the leading end of said member, means carried by said frame yieldingly supporting the trailing end of said member, means limiting movement of said frame by the doors and means to retard the return movement of said frame. 30
7. In a door closing device, a door engaging member, a pivotally jointed frame to which said door engaging member is pivotally connected at one end thereof, means carried by said frame yieldingly supporting the other end of said member, stops limiting movement of said frame in both directions and means retarding movement of said frame in one direction. 35
8. In a door closing device, a door engaging member, a pivotally jointed and supported frame to which said door engaging member is pivotally connected at one end thereof, means yieldingly supporting the other end of said member above said frame, said frame raising said member as said frame and member are moved by a door, and a stop to limit the movement of said frame and cause the door to pass over said member, said yielding means permitting the end of 40 said member to be forced downward as the door passes over said member.
9. In a door closing device, a door engaging member, a pivotally jointed and supported frame to which said door engaging member is pivotally connected at one end 45
- thereof, means on said frame supporting the other end of said member above said frame, a stop holding said frame in a normal position for engaging said member with an open door on a moving car, said frame raising said member as said frame and member are moved by the door, and a stop to limit the movement of said frame and cause the door to pass over said member, said means yielding to permit said member to be forced down as the door passes over said member. 50
10. In a door closing device, a support, a plurality of links pivotally connected to said support, a tie member pivotally connected to the upper ends of said links, a door engaging member pivotally connected to the links at one end and yieldingly supported on said tie member at the other end. 55
11. In a door closing device, a support, a plurality of links pivotally connected to said support, a tie member pivotally connected to the upper ends of said links, a door engaging member having one end pivotally connected to one of said links at the joint between said link and tie member, springs supporting the other end of said door engaging member from said tie member, stops engaging said links to limit movement thereof in both directions and a counterweight to slow movement of said links in one direction. 60
12. In a door closing device, a support, a plurality of links pivotally connected to said support, a tie member pivotally connected to the upper ends of said links, a door engaging member pivotally connected at one end to said tie member and yieldingly supported at its other end from said tie member, means engaging said links to limit movement thereof and means slowing the latter part of the movement of said links in one direction. 65
13. In a door closing device, a support, a frame pivoted thereto, a door engaging member carried by and pivotally connected to said frame, a stop to limit movement of said frame in both directions and means to retard movement of said frame in one direction. 70
14. In a device of the kind described, a pivotally mounted frame, a stop for normally holding the frame in a position to be engaged by the open door of a moving car, said door causing pivotal movement of said frame in a direction such as to urge the door to closed position, and stop means for limiting the shifting movement of said frame. 75
15. In a device of the kind described, a pivotally mounted frame, a stop for normally holding the frame in a position to be engaged by the open door of a moving car whereby said door causes pivotal movement of said frame in a direction urging the door to closed position, and stop means for limiting the shifting movement of said frame, said frame including a yieldable member with which the door directly engages as it passes thereover. 80
16. In a door closing device, a support, a frame pivotally mounted thereon, a door engaging member carried by the frame and pivotally connected to the frame at one end, means yieldingly supporting the other end of the door engaging member, a stop holding the frame in a normal position for engaging the door engaging member with an open door on a moving car, said frame raising the door engaging member as the door passes over the member, and a stop to limit the movement of the frame and cause the door to pass over the member, said means yielding to permit the member to be forced down as the door passes over the member. 85
17. In a door closing device, a support, a frame pivotally mounted thereon, a door engaging member carried by the frame and pivotally connected to the frame at one end, means yieldingly supporting the other end of the door engaging member, a stop holding the frame in a normal position for engaging the door engaging member with an open door on a moving car, said frame raising the door engaging member as the door passes over the member, and a stop to limit the movement of the frame and cause the door to pass over the member, said means yielding to permit the member to be forced down as the door passes over the member. 90
18. In a door closing device, a support, a frame pivotally mounted thereon, a door engaging member carried by the frame and pivotally connected to the frame at one end, means yieldingly supporting the other end of the door engaging member, a stop holding the frame in a normal position for engaging the door engaging member with an open door on a moving car, said frame raising the door engaging member as the door passes over the member, and a stop to limit the movement of the frame and cause the door to pass over the member, said means yielding to permit the member to be forced down as the door passes over the member. 95
19. In a door closing device, a support, a frame pivotally mounted thereon, a door engaging member carried by the frame and pivotally connected to the frame at one end, means yieldingly supporting the other end of the door engaging member, a stop holding the frame in a normal position for engaging the door engaging member with an open door on a moving car, said frame raising the door engaging member as the door passes over the member, and a stop to limit the movement of the frame and cause the door to pass over the member, said means yielding to permit the member to be forced down as the door passes over the member. 100
20. In a door closing device, a support, a frame pivotally mounted thereon, a door engaging member carried by the frame and pivotally connected to the frame at one end, means yieldingly supporting the other end of the door engaging member, a stop holding the frame in a normal position for engaging the door engaging member with an open door on a moving car, said frame raising the door engaging member as the door passes over the member, and a stop to limit the movement of the frame and cause the door to pass over the member, said means yielding to permit the member to be forced down as the door passes over the member. 105
21. In a door closing device, a support, a frame pivotally mounted thereon, a door engaging member carried by the frame and pivotally connected to the frame at one end, means yieldingly supporting the other end of the door engaging member, a stop holding the frame in a normal position for engaging the door engaging member with an open door on a moving car, said frame raising the door engaging member as the door passes over the member, and a stop to limit the movement of the frame and cause the door to pass over the member, said means yielding to permit the member to be forced down as the door passes over the member. 110
22. In a door closing device, a support, a frame pivotally mounted thereon, a door engaging member carried by the frame and pivotally connected to the frame at one end, means yieldingly supporting the other end of the door engaging member, a stop holding the frame in a normal position for engaging the door engaging member with an open door on a moving car, said frame raising the door engaging member as the door passes over the member, and a stop to limit the movement of the frame and cause the door to pass over the member, said means yielding to permit the member to be forced down as the door passes over the member. 115
23. In a door closing device, a support, a frame pivotally mounted thereon, a door engaging member carried by the frame and pivotally connected to the frame at one end, means yieldingly supporting the other end of the door engaging member, a stop holding the frame in a normal position for engaging the door engaging member with an open door on a moving car, said frame raising the door engaging member as the door passes over the member, and a stop to limit the movement of the frame and cause the door to pass over the member, said means yielding to permit the member to be forced down as the door passes over the member. 120
24. In a door closing device, a support, a frame pivotally mounted thereon, a door engaging member carried by the frame and pivotally connected to the frame at one end, means yieldingly supporting the other end of the door engaging member, a stop holding the frame in a normal position for engaging the door engaging member with an open door on a moving car, said frame raising the door engaging member as the door passes over the member, and a stop to limit the movement of the frame and cause the door to pass over the member, said means yielding to permit the member to be forced down as the door passes over the member. 125
25. In a door closing device, a support, a frame pivotally mounted thereon, a door engaging member carried by the frame and pivotally connected to the frame at one end, means yieldingly supporting the other end of the door engaging member, a stop holding the frame in a normal position for engaging the door engaging member with an open door on a moving car, said frame raising the door engaging member as the door passes over the member, and a stop to limit the movement of the frame and cause the door to pass over the member, said means yielding to permit the member to be forced down as the door passes over the member. 130

16. In a door closing device, a support, a frame pivoted to the support, a door closing member pivotally connected to said frame, and a stop member cooperatively associated with the frame for limiting pivotal movement of the latter in both directions. 70
17. A closing device for drop bottom car doors comprising a support, a frame pivotally connected to the support, a door engaging member carried by the frame and with which the doors contact to be forced to closed position, and yielding means on the frame for absorbing shocks to which the door engaging member is subjected by the doors. 75
18. A door closing device for drop bottom cars comprising a pivotally mounted frame, and a door engaging member pivotally and yieldably supported by said frame. 80
19. In a door closing device, a frame comprising parallel pivoted side members, a door engaging member carried by the frame and pivotally connected at one end thereto, and a stop arranged between said side members for limiting pivotal movement of said frame. 85
20. In a door closing device, a frame comprising parallel side members, a base to which said side members are pivoted for shifting movement in two directions, a door engaging member pivotally connected at one end to said frame, resilient means for yieldingly supporting the other end of said door engaging member, and a stop arranged between said side members for limiting shifting movement of the frame in both directions. 90
21. In a door closing device, a base, a frame pivotally secured to the base and including an upper frame member, a door engaging member supported by the frame and pivotally connected at one end thereof to said frame, and yielding means for supporting the other end of said door engaging member. 95
22. In a door closing device, a base, a frame pivotally secured to the base and including an upper frame member, a door engaging member supported by the frame and pivotally connected at one end thereof to said frame, and yielding means interposed between the upper frame member and the other end of said door engaging member for resiliently supporting the door engaging member at said other end. 100
23. In a door closing device, a support, a frame mounted on the support and capable of limited shifting movement in two directions, and a door engaging member arranged longitudinally of the frame and having one end thereof pivoted to said frame. 105
24. In a door closing device, a door engaging member, a pivotally jointed and supported frame for supporting said member and to which the latter is pivotally connected at one end, resilient means supporting the other end of said member, means with which said frame cooperates for limiting pivotal movement thereof and for normally holding said frame inclined to the vertical, said door closing device being arranged between track rails in a position such that the door engaging member contacts the open door of a moving car whereby movement of said car shifts the frame on its pivotal mounting. 110
25. In a door closing device, a support, a frame pivoted to the support and normally arranged at an angle inclined to the vertical, a door engaging member pivotally secured at one end to said frame, and means on the frame for yieldingly supporting the other end of said member, the frame being positioned between track rails and the pivoted end of said door engaging member being so arranged relative to the path of movement of a moving car as to be engaged by an open car door whereby continued movement of the car causes the door to shift the frame from its normal position towards a vertical position to cause said door engaging member to force the door to closed position. 115
26. In a door closing device, a support, a frame pivotally secured thereto, a door engaging member arranged longitudinally of the frame and having one end pivotally connected to said frame, and a stop mounted on the support for normally holding the frame at an angle inclined to the vertical. 120
27. In a door closing device, a support, a frame pivotally secured thereto, a door engaging member arranged longitudinally of the frame and having one end pivotally connected to said frame, and a stop mounted on the support for normally holding the frame at an angle inclined to the vertical and for limiting pivotal movement of said frame in both directions. 125
28. In a door closing device for drop bottom cars, a support arranged between track rails, a frame pivoted to the support and including spaced connected links, and a stop member intermediate the links and cooperating with the latter to limit pivotal movement of the frame in both directions. 130
29. In a door closing device for drop bottom cars, a support arranged between track rails, a frame pivoted to the support and including spaced upright frame elements, and a stop member intermediate the frame elements and cooperating with the latter to limit pivotal movement of the frame in both directions, said stop member being so formed and arranged as to normally retain the frame elements at an angle inclined to the vertical. 135
30. In a door closing device, a door engaging member, and a pivotally jointed and supported frame to which said door engaging member is pivotally and resiliently secured, said engaging member being adapted to be contacted by an open door of a moving car to move said frame on its pivot to permit the 140

door engaging member to be elevated whereby to force the door to closed position.

31. A door closing device for drop bottom cars comprising a support arranged between track rails, a frame pivoted to the support, a fixed abutment cooperatively associated with the frame for limiting pivotal movement of the latter in both directions, said frame being arranged in the path of movement of an open door of a moving car and being adapted to contact said door and to urge the same to closed position upon continued movement of the car, and door engaging means with which an open door of said moving car contacts to partially close the door prior to contact of said door with said door closing device.

32. In a device of the kind described, a pivotally and yieldably mounted door closing member, and shiftable means supporting said member in a position to engage the open door of a moving car.

33. In a device of the kind described, a pivotally and yieldably mounted door closing member, shiftable means supporting said member in a position to engage the open door of a moving car, and fixed abutment means for limiting the movement of said shiftable means.

30 In witness whereof I have hereunto set my hand.

WILLIAM F. DIETRICHSON.
